UNITED STATES PATENT OFFICE.

ARTHUR E. ROPE, OF BROOKLYN, NEW YORK.

RUBBER HEEL.

1,426,218.

Specification of Letters Patent. Patented Aug. 15, 1922.

Application filed May 28, 1921. Serial No. 473,471.

To all whom it may concern:

Be it known that I, ARTHUR E. ROPE, a citizen of the United States, and resident of the city of New York, borough of Brooklyn, county of Kings, and State of New York, have invented a new and Improved Rubber Heel, of which the following is a full, clear, and exact description.

My invention relates to improvements in rubber heels, and more particularly to rubber or other composition heels adapted to be secured to the lower faces of the ordinary leather heels to provide the necessary elastic cushions.

15 A further object is to provide rubber heels of the character stated which are formed of a plurality of sections so that the sections of the respective heels can be readily interchanged to compensate for wear and thus 20 compel the heels to wear evenly through the life of the shoe.

A further object is to provide improved means for securing the heel sections to the shoe heel so that said securing means shall 25 not only be effective in operation but insure a proper assemblage of the sections and can be operated by any one of average intelligence and not requiring skilled labor.

With these and other objects in view the 30 invention consists in certain novel features of construction and combinations and arrangements of parts as will be more fully hereinafter described and pointed out in claims.

35 The accompanying drawings:

Figure 1 is a view in bottom plan of a pair of shoes equipped with my improved rubber heels.

40 Figure 2 is a view of the inside elevation of a shoe with my improved rubber heel thereon.

Figure 3 is a view in section on the standard line 3—3 of Figure 1.

45 1 represents a shoe, boot, slipper or other footwear having the ordinary sole 2 and the ordinary leather heel 3.

While in Figure 1 I illustrate in bottom plan a pair of shoes equipped with my improved rubber heels, it is obvious that a detailed description of one shoe and heel construction will apply alike to both, and particular attention is called to the fact that my improved rubber heels are precisely alike on both shoes.

55 While I shall employ the term rubber heel to distinguish my improved rubber heel

from the ordinary leather heel of the shoe, I would have it understood that the invention is not limited to the material or composition of the heel as this can be varied to suit the 60 trade.

My improved heel comprises front and rear sections 4 and 5, said sections 4 and 5 having a preferably straight meeting edge 6, extending transversely of the heel, although the exact line of juncture or angle of line can be varied without departing from the invention.

Each section 4 and 5 is secured to the shoe heel 3 by means of a pair of screws 7, these 70 screws being of the ordinary headed type and projected through washers 8, countersunk in recesses 9 in the heel sections.

In addition to the screws 7 above described the sections 4 and 5, at their meeting edges 75 and preferably at a point equally spaced from the screws 7, are coupled and secured to the leather heel 3 by means of a fifth screw 10. This screw 10 is projected through a washer 11, located in countersunk registering semi-cylindrical recesses 12 in the heel sections 4 and 5 so that by reason of the pressure of the screw head against the washer the sections are rigidly secured and are guided or directed into proper assembled position.

As it is one of the primary objects of my invention to provide heels of sections which are interchangeable from one shoe to the other, it is important that the sections when 90 so changed shall be properly placed and this central screw 10 with this washer 11 will fit in the recesses 12 and serve to insure a proper position of the sections.

It is obvious that either the front or rear 95 sections of the heels can be interchanged as necessity may arise, but it is more frequently true that it will be necessary to change the rear sections because of the tendency to wear the heels on one side. In any event the heels 100 are perfectly interchangeable so that the wearer can change the sections as he may desire to give the best results.

By providing rubber heels of the character stated an economy to the user is insured because not only is the wear of the heels extended beyond that of the ordinary heel but in the event that one section needs to be replaced by a new section this can be done at a very low cost.

110 While I have illustrated a preferred embodiment of my invention, it is obvious that

various slight changes might be made in the general form and arrangement of parts without departing from my invention and hence I do not limit myself to the precise details set forth, but consider myself at liberty to make such changes and alterations as fairly fall within the spirit and scope of the appended claims.

I claim:—

- 10 1. In combination with a shoe heel, a rubber heel comprising a pair of sections, means for attaching each section to the shoe heel, said rubber heel sections having recesses located in alinement with one another and extending inward from their meeting edges to provide a counter-sunk opening through them when the sections are fitted together, means for mounting in the coun-
- 15

tersunk opening to engage both sections, and means for attaching said section engaging 20 means to the shoe heel.

2. The combination with a shoe heel, of a rubber heel lift comprising a pair of sections, a pair of screws projecting through each of the heel sections and screwed into 25 the shoe heel, said rubber heel sections having at the center of their meeting edges a pair of semi-cylindrical registering recesses, one recess being appreciably larger in diameter than the other, a washer in the larger 30 recess, a screw projected through the washer and through the smaller pair of recesses and screwed into the shoe heel, and a head on said screw located against the washer and countersunk within the larger recesses.

ARTHUR E. ROPE.
